UNITED STATES PATENT OFFICE.

PHILIP LANE SCOTT, OF CHICAGO, ILLINOIS, ASSIGNOR TO SUPER-DIESEL TRACTOR CORPORATION, OF LA PORTE, INDIANA, A CORPORATION OF NEW YORK.

ATOMIZER FOR INTERNAL-COMBUSTION ENGINES AND THE LIKE.

Application filed August 8, 1921. Serial No. 490,814.

My invention relates to an atomizing nozzle for internal combustion engines and the like and has particular reference to size, shape and arrangement of the nozzle which guides the atomized jet of liquid and which guides and controls it after it has left the first atomizing passage or point and before it reaches the zone into which it is discharged.

10 I have found that when liquids are ejected through an exceedingly minute passage at exceedingly high velocities and exceedingly high pressure, a very fine atomization results. I have also found that if the jet is directed against a surface from which it can rebound or by which it can be deflected, if conditions are right, the jet is controlled, deflected and perhaps reatomized by its impingement upon such surface so as to give a more satisfactory and uniform spray. Without control the spray is apt to be ragged and poorly distributed. By imposing upon it the above described control the form of the spray is made uniform and of the desired proportion, the raggedness is eliminated and the degree of homogeneity of the spray is improved.

15 I have also found by experience that there seems to be a well defined limit beyond which the number of impingements of the jet against such a surface or surfaces should not be increased.

20 I have found by experiment that if I associate an atomizing nozzle or valve with a relatively long passage and if the size of that passage is such that the jet rushing out from the primary spraying or atomizing nozzle impinges on the wall of that passage at least once before it is discharged into the zone where it is to be received, satisfactory atomizing will take place.

25 I have also found that if the passage is long enough so that assuming the angle of incidence and reflection, to be the same as that of a ray of light passing in the same direction as the spray, and that if the nozzle is so long that more than six impingements upon the surface take place, then atomization is not satisfactory and there seems to be a tendency for recondensation to take place. 50 In other words, if the jet is discharged from the primary atomizing passage and impinges upon the walls of the guiding and controlling passage at an angle other than a right angle with respect to that passage, then if 55 the passage is so long that the jet moves back and forth from side to side it does not impinge upon the walls more than six times, satisfactory atomization will take place.

30 It is possible of course that there are eddy currents, turbulence and other disturbances taking place in the passage; it is possible that a high pressure, high velocity jet does not act as a ray of light would; it is possible that the angles of incidence and reflection may 60 be changed as the jet passes down through the passage, but the fact remains that if the proportion, size, shape and arrangement of parts are such that if the angle of reflection of the jet were to be the same as its angle 65 of incidence and if it were to reflect back and forth and across the passage so as to impinge at least once and not more than six times upon the walls of the passage, then 70 there will result a very high degree of atomization and a very uniform and well regulated and controlled spray of atomized material.

35 This passage which imposes the control upon the spray differs distinctly from passages somewhat similar in mechanical structure and location, used in valves in the prior art, in that the passage referred to here is not at any time completely filled with the atomized liquid due to the fact that its diameter is many times greater than the thickness of the jet as it issues from the atomizing 75 passage.

40 In order to illustrate the range within which the dimensions and shapes of the parts 80 cooperating to produce the desired result in my invention are found, I have worked out a formula illustrated by the drawings as follows: wherein the invention is illustrated more or less diagrammatically:

Figure 1 is a section through an atomizing nozzle;

Figure 2 is a section on an enlarged scale

through a part of the nozzle shown in Figure 1, suggesting the path of the jet of atomized material;

5 Figure 3 is a detailed showing of a modified form of spray nozzle associated with the guide passage;

Figure 4 is a section at right angles to the section of Figure 3;

10 Figure 5 is a plan view of the disc of Figures 3 and 4;

Figure 6 is a diagrammatic sketch showing a spray nozzle in which the proportions are slightly different;

15 Figure 7 is a diagrammatic showing illustrating the mathematics of the relation of the parts and dimensions.

Like parts are designated by like characters throughout.

20 A is a valve housing having a longitudinal passage A' therein. A² is a sleeve, screw threaded in the valve housing having a passage A⁴ in line with a passage A⁵ which in turn communicates with the passage A'. A⁶ is a fluid supply pipe communicating with 25 the passage A⁴ and connected up with the sleeve A² by the coupling A⁷.

25 B is a cap, screw-threaded on the discharge end of the valve housing. The housing is itself screw threaded in the wall B' 30 of an engine cylinder or the pressure chamber or any other suitable apparatus where this valve might be appropriately positioned. The end of the valve housing is counter-sunk as at B². B³ is a packing washer arranged 35 within the counter-sunk end about its periphery. B⁴ is a spray disc apertured as at B⁵ and the aperture is adapted to be closed by a blunt plug or needle valve B⁶ on the end of the valve stem B'. The stem is enlarged at its upper end, surrounded by a 40 packing B⁸ and compressed by a crank B⁹. The end of the valve stem is screw-threaded as at B¹⁰ and a hand wheel B¹¹ has a screw-threaded engagement therewith being held 45 against longitudinal displacement on the yoke B¹² so that the manipulation of the hand wheel may move the plug or needle valve toward or from the spray disc.

50 Under normal conditions, this needle valve is held seated on the disc so as to close the aperture B⁶ until oil or other liquid is forced into the valve housing under sufficient pressure to deflect the spray disc which is more or less flexible and permit discharge of the 55 liquid to be sprayed between the needle valve and the disc and through the aperture in the disc.

60 The invention with which I am particularly concerned at the present time lies in the particular portions of the needle valve, the aperture in the disc, the seat of the needle valve on the disc, and the inclination of that seat and that is more particularly illustrated in Figures 2 to 6.

65 In Figure 2 is shown a very blunt needle

valve B⁶ having a relatively broad seat on the valve disc as shown at C. This disc is shown in the unseated position very much magnified of course. The dotted line C' shows the path of the liquid between the needle valve and its seat on the disc and it will be observed that this dotted line path impinges first on one side of the aperture B⁶ and then on the other, there being in the present connection, room for six impingements. As previously suggested, it is not certain that these six impingements take place but the arrangement is such that if the angle of incidence and reflection were the same in every case, these six impingements could take place.

70 In Figure 3 is shown a slightly different or modified form of disc in which there is a relatively heavy disc D having a central boss D' with a passage D² therein and this passage is closed by two separate flat plates D³, D⁴ engaging edge to edge and cut away or nicked at D⁵ in line with the passage D². The front elevation of one of these plates is shown in Figure 4 and it will be noted here that the liquid which may be forced out between the nicked portion of these plates will come out at a much more acute angle and may impinge only twice on the walls of the passage. In Figure 5 is shown a plan view of Figures 3 and 4.

75 Figure 6 shows a slightly different arrangement wherein the heavy plate E with its boss E' and passage E² carries a thicker plate E³ in which is disposed a seat E⁴ in engagement with a sharper needle point E⁵ such that when the valve is unseated, there will be a possibility of but a single impingement of the jet across the seat against the wall of the passage.

80 Figure 7 shows the appropriate dimensions for an arrangement which will carry out the subject of my invention, the arrangement being such that the formula $l=k(a \times \tan \alpha)$; in which a equals the diameter of the hole, l equals the length of the hole and α equals the angle between the seat and the plane perpendicular to the axis of the hole. When this is the case, if the constant k is equal to at least one and is not greater than six, then satisfactory atomization will take place.

85 In the preferred form shown in Figures 1, 2, 6, and 7 the valve stem is of the self-positioning type, and it is constructed and adapted to position itself within the valve, the arrangement being such that the stem, and particularly the needle point, will as nearly as possible be self-centering. In practice, however, experience has shown that the needle point is frequently unsymmetrical in its seating, and that it will thus produce an unsymmetrical jet of liquid, which is discharged into the guide passage.

90 It will be understood that I have, except

in Figure 1, shown my device in a greatly magnified condition and I have shown it as if the deflection resulted in and by a pas-
sageway or opening all the way round the valve between the needle valve and the seat. Obviously in practice, what happens is that there will be sufficient distortion to permit a slight opening between the valve and its seat at some one place only and it will be
10 through the very narrow passage just formed that the liquid will be discharged.

The clearance between the valve and the valve seat is in practice so small that it may frequently be not greater in thickness than one hundredth of the width of the guiding passage in the disc, although it may vary from this figure it has been found preferable to have it never larger than one-twenty-fifth the width of the guide passage.

20 I claim:

1. An atomizing nozzle comprising a control passage, a valve seat in advance of one end of said passage, a valve head adapted to engage the seat and cut off communication between the interior of the nozzle and said passage, the valve when opened producing a minute passage between the valve head and the valve seat, the seat being inclined to the longitudinal axis of the control passage, the relation between the three dimension factors involved following the formula, $l=k(a \times \tan \alpha)$, in which "a" equals the diameter of the control passage, "l" equals the length of the control passage and "alpha" equals the angle between the seat and the plane perpendicular to the axis of the control passage, and in which the value of the constant "k" is at least one and not more than six.

40 2. An atomizing nozzle comprising an elongated control passage, a valve seat im- mediately in advance of one end of said

passage, a valve head adapted to engage the seat and cut off communication between the interior of the nozzle and said passage, 45 the valve when opened producing a minute radial passage between the valve head and seat, the seat being inclined to the longitudinal axis of the control passage, the relation between the three dimension factors involved following the formula, $l=k(a \times \tan \alpha)$, in which "a" equals the diameter of the control passage, "l" equals the length of the control passage and "alpha" equals the angle between the seat and the 50 plane perpendicular to the axis of the control passage, and in which the value of the constant "k" is at least one and not greater than 6.

3. An atomizing nozzle comprising an elongated control passage, a valve immediately in advance of one end of said passage, said valve adapted when closed to cut off communication between the interior of the nozzle and said passage, the valve when opened providing a minute passage between the interior of the nozzle and the said elongated control passage, the valve opening being inclined to the longitudinal axis of the control passage, the relation between the three dimension factors involved following the formula $l=k(a \times \tan \alpha)$, in which "a" equals the diameter of the control passage, "l" equals the length of the control passage, and "alpha" equals the angle between the plane of the valve opening and the plane perpendicular to the axis of the control passage, in which the value of the constant "k" is at least one and not more than six.

Signed at Chicago, county of Cook and State of Illinois, this 6th day of August, 1921.

PHILIP LANE SCOTT.
